CLARENCE B. BOWLING AND LEROY B. BENNETT, OF DETROIT, MICHIGAN, ASSIGNEES
TO BOWLING DENTAL MANUFACTURING CO., OF DETROIT, MICHIGAN, A CORPOR-
ATION OF MICHIGAN.

DENTAL-FLOSS HOLDER.

1,250,953.

Specification of Letters Patent. Patented Dec. 25, 1917.

Application filed March 31, 1917. Serial No. 159,033.

To all whom it may concern:

Be it known that we, CLARENCE B. BOWLING and LEROY B. BENNETT, citizens of the United States of America, residing at Detroit, in the county of Wayne and State of Michigan, have invented certain new and useful Improvements in Dental-Floss Holders, of which the following is a specification, reference being had therein to the accompanying drawings.

This is an improvement in connection with a dental floss holder disclosed in Patent No. 1,158,890, granted to one of the present applicants under date of November 15, 1915. In this patent there is disclosed a simple, durable and inexpensive floss holder having novel and efficient means for holding the floss whereby the active portion of the floss may be readily renewed and tightened, 20 and while this holder is efficient in many respects yet the present invention aims to provide a holder possessing many advantages from the standpoint of a user and manufacturer.

25 The first improvement may be considered in connection with the bow or means of holding the floss in an active position. In the patent referred to, the floss is disposed in parallelism with the longitudinal side of 30 the bow, and it has been found that the floss holder could not be conveniently manipulated in the mouth, particularly in proximity to a molar tooth or one in the back part of a jaw. The holder necessitates 35 the mouth being wide open during such operation, much to the inconvenience of the manipulator of the holder, so we discovered that by holding the floss at an angle relative to the back of the bow, it was possible 40 to manipulate our improved holder in the mouth with the mouth almost closed.

Furthermore, the angularity of the floss relative to the bow permits of tooth cavities or space between teeth being more readily 45 reached without any danger of the gums being injured.

The second improvement resides in the means for drawing the floss taut relative to the bow. In the patent above referred to 50 an arm and a nut were employed, both being separate, consequently the arm could not follow the nut when being retracted. Now, we connect these elements so that the arm will be at all times removed longitudinally 55 of the bow with the nut, which is quite a

convenience when renewing an active portion of the floss.

The third improvement is that of arranging a knife at the outer end of the holder body so that the floss can be easily cut. The 60 disposal of the knife is such as not to injure the hand manipulating the holder, or any fabric that may contact with the holder.

Besides the above there are other improvements that will hereinafter appear as 65 the invention is better understood, and reference will now be had to the drawing, wherein—

Figure 1 is a longitudinal sectional view of the floss holder; 70

Fig. 2 is a side elevation of the same;

Fig. 3 is a plan of a portion of the holder;

Fig. 4 is a cross sectional view of a bow;

Fig. 5 is a detail view of a portion of an adjustable bow arm, and 75

Fig. 6 is a longitudinal section of a portion of a modified form of holder.

In the drawing, 1 denotes a suitable handle made of a suitable material and having one end thereof closed, as at 2, while the opposite end is interiorly screwthreaded, as at 3, to receive a cap or plug 4 having a nose portion 5. The tubular handle 1 constitutes a container for a cap or cartridge of floss 6 and this floss is arranged so that it may be 80 readily reeled off or withdrawn through a longitudinal opening 7 in the cap 4, said opening being to one side of the longitudinal axis of said cap, and of such diameter that the floss can be easily threaded there- 85 through and readily pulled out of the tubular handle. 90

Mounted in the cap 4 is the inner end of a rod 8 and the greater part of said rod is screwthreaded, as at 9, for a nut 10. The 95 nut 10 is preferably knurled so as to facilitate rotation and the inner end of said nut has a collar 11 engaging under the flange 12 of a bearing 13 for an arm 14. The bearing 13 is slidable on flat facets 15 of the 100 threaded portion of the rod 8 and is consequently held against rotation when being shifted longitudinally of the rod by the nut 10. The flat facets in connection with the rod obviates the necessity of using 105 feathers or keys and afford a more substantial seat for the bearing 13 of the arm 14.

The outer end of the rod 8 terminates in a fixed arm 16 disposed at right angles to the rod 8 and of greater length than the 110

arm 14, so that when the floss connects the arms 14 and 16, the strand of floss held by said arms will be disposed at an acute angle relative to the rod 8, and this angle may be varied by lengthening or shortening said arms. The rod 8 and arms 14 and 16 constitute a bow and outer end or extremity of each arm has an apertured head 17 with the aperture of said head intersected by a bifurcation or slot 18, thus providing opposing arms around either of which the floss may be wound and anchored relative to the arms 14 and 16. The heads 17 permit of the floss being easily and quickly placed in engagement with the arms and after a strand of floss has been fixed relative to said arms, the nut 10 can be rotated to draw the floss taut, thus placing the strand of floss in such condition and position that it can be used in the mouth.

The nose 5 of the cap or plug 4 is provided with a member or knife 19 radially disposed relative to the axis of the cap or plug and the inner end of the knife is adapted to engage one of the facets of the rod and thus prevent rotation of the same. The outer end of the knife 19 protrudes sufficiently from the side of the nose 5 to permit of the floss being placed in engagement therewith and said knife has a cutting edge, and is preferably triangular in cross section. After a strand of the floss has been used the permanent knife 19 permits of the strand being quickly severed, the used strand removed, and a new piece withdrawn from the tubular handle and connected to the arms 14 and 16 of the bow.

In Fig. 6 there is illustrated a slight modification of our invention wherein the bow is made in two sections 20 and 21 articulated by a nut or turn-buckle 22 so that the section 21 carrying the outer arm 23 may be moved to and from the section 20. Connected to the nut 22 is a short arm 24 and as the nut 22 is adjusted, the short arm is also moved relative to the arm 23. The arms 23 and 24 have the usual heads 17 so that a piece of floss may be disposed at an angle to the bow. The sections 20 and 21 are also connected, as at 25, so as to maintain the arms 23 in the same plane as the arms 24. Furthermore, the handle of the holder has a cap or plug 26 provided with a bayonet

slot and pin connection 27, so that the cap or plug may be partially rotated and then shifted into the handle of the holder so as to reduce the longitudinal dimensions of the device and permit of it being readily carried in a vest pocket.

It is thought that the operation and utility of the floss holder will be apparent without further description, and while in the drawing there is illustrated a preferred embodiment of our invention, it is to be understood that the structural elements are susceptible to such changes, in size, shape, material and manner of assemblage as fall within the scope of the appended claims.

What we claim is:—

1. In a dental floss holder, a bow comprising arms of different length adapted to hold a strand of floss at an angle to said bow, and means on said bow constantly in engagement with one of the arms thereof adapted for shifting the arm. 75

2. In a dental floss holder, a bow comprising arms of different length adapted for holding a piece of floss at an angle relative to said bow, and a nut on said bow constantly in engagement with one of the 80 arms thereof for adjusting said arm relative to said bow.

3. In a dental floss holder comprising a handle serving as a container for floss, a bow supported from said handle comprising arms of different length adapted to hold a strand of the floss at an angle relative to said bow, and means on said bow adapted for adjusting one of the arms thereof. 85

4. In a dental floss holder, a tubular handle adapted to contain floss, an apertured cap carried by said handle adapted to have the floss extend therethrough, a bow carried by said cap comprising a long and short arm adapted to hold a strand of the 95 floss, and means on said bow constantly in engagement with the short arm for shifting said arm longitudinally of said bow.

In testimony whereof we affix our signatures in presence of two witnesses.

CLARENCE B. BOWLING.
LEROY B. BENNETT.
